United States Patent Office.

JOSEPH H. BAIRD, OF OAKVILLE, CONNECTICUT.

Letters Patent No. 90,914, dated June 8, 1869.

IMPROVED CONVEYER, TO TRANSFER BLANKS FROM A PUNCHING-PRESS.

The Schedule referred to in these Letters Patent and making part of the same.

To all whom it may concern:

Be it known that I, JOSEPH H. BAIRD, of Oakville, in the county of New Haven, and State of Connecticut, have invented a new and improved Attachment for Receiving and Conveying Blanks from Punching-Presses; and I do hereby declare the following to be a full, clear, and exact description of the construction and operation of the same, reference being had to the accompanying drawings, in which—

Figure 1 is a side elevation of the attachment, and Figure 2, a top view of the same.

Similar letters of reference indicate like parts in the several drawings.

My invention has for its object the collecting and arranging of the blanks, as they are cut by the press, in continuous layers, so that quantities of them may be readily transferred, and fed to other machines in which the successive operations are performed, in manufacturing hinges and other articles from metal blanks or plates. To this end—

My invention consists in the employment and use of a curved trough or guide, which is attached, in a proper manner, to the die-block or bed of a punching-press, as will be fully set forth hereafter.

To enable others skilled in the art to make and use my invention, I will describe its construction and operation.

In proper position with reference to the press, I arrange a curved trough, A, firmly bolted or otherwise connected with the floor or the frame of the press.

This trough, the form of which is clearly shown in the drawings, is attached, at one end, to the under

side of the bed B, immediately beneath the die C, and at the other end is connected with an extension, A', represented in blue lines in the drawings.

Proper ledges or sides, *a a*, and a guide, *b*, are provided for holding the blanks in place.

The extension, A', serves as a table upon which the blanks are received, as they rise in the trough.

The bottom is inclined, to retain the blanks in place, and one ledge or side is removed, to enable the blanks to be readily removed, in the desired quantities at a time, in boxes, or otherwise transferred to the different machines by which the various operations necessary to the forming of hinges and other articles are performed.

As the blanks *c* are cut by the press, from the metal fed thereto, they drop from the die into the space between the sides of the trough and the guide *b*, and as the operation of the press continues, the accumulated blanks in the trough, immediately under the die, press the foremost blanks up the inclined part of the trough, on to the receiving-table or extension A', from whence they are transferred to the other presses or machines, as before described.

Having thus fully described my invention,

I claim the improved conveyer, of the form described, constructed, arranged, and operating substantially in the manner and for the purposes set forth.

JOSEPH H. BAIRD.
